CLAIM

The ornamental design for a make-up compact case, as shown and described.

DESCRIPTION

FIG. 1 is a perspective view of a make-up compact case showing an embodiment of my new design;

FIG. 2 is front elevational view of FIG. 1;

FIG. 3 is a rear elevational view of FIG. 1;

FIG. 4 is a right side view of FIG. 1, the left side view being the mirror image thereof;

FIG. 5 is a top plan view of FIG. 1;

FIG. 6 is a bottom plan view of FIG. 1;

FIG. 7 is a perspective view of a make-up compact case showing a second embodiment of my new design;

FIG. 8 is a front elevational view of FIG. 7;

FIG. 9 is a rear elevational view of FIG. 7;

FIG. 10 is a right side view of FIG. 7, the left side view being the mirror image thereof;

FIG. 11 is a top plan view of FIG. 7; and,

FIG. 12 is a bottom plan view of FIG. 7.
